STERILIZING DETERGENT COMPOSITION AND METHOD OF USE

**John Charles Lovell Resuggan, London, England,
assignor to Industrial and Commercial Deter-
gents Limited, London, England**

No Drawing. Application February 19, 1948, Serial No. 9,636. In Great Britain March 28, 1946

3 Claims. (Cl. 252—106)

This invention relates to a method of cleaning milk bottles and other returnable containers for food products and beverages and to detergents compositions more particularly for use in machines for washing milk bottles, beer bottles and like containers for edible and potable products and for cleaning apparatus and equipment concerned in the manufacture and transport of such products. Detergents for these purposes are required to have a combination of properties peculiar to the particular purpose for which they are required. Not only must they have the power of quickly removing traces of food products adhering firmly to the bottle or other object to be cleaned but in order that, e. g., bottle washing machines may function correctly any excessive foaming must be avoided and it is also necessary to commercially sterilize the bottles or other equipment. At the same time it is necessary that in sterilizing no poisonous material should be used.

Proposals have previously been made for using alkyl quaternary ammonium compounds as surface active agents and it is known that such compounds possess bactericidal and bacteriostatic properties. It is also known to incorporate quaternary ammonium compounds with other detergents but compounds containing upwards of twelve carbon atoms in the alkyl group possess considerable foaming properties, which render them quite unsuitable for bottle and like cleaning equipment.

The lack of an efficient detergent which has adequate bactericidal properties and does not foam has made it necessary hitherto to employ caustic alkalis at a high temperature in bottle washing equipment, the high temperatures causing considerable breakages of bottles and the caustic alkalis being dangerous to the operatives. It is an object of this invention to provide a method of cleaning and sterilizing milk bottles and like containers and a composition which will have adequate bactericidal potency for this purpose so that what is known as a "commercially sterile" bottle or other container is obtained without using strong alkalis, or high temperatures, and in particular, a composition which will not foam unduly.

It has now been discovered that by a suitable selection of the substituent groups in an organic quaternary ammonium compound, it is possible to produce a composition which will fulfil the above requirements without foaming excessively or even

as much as the normal strong alkalis foam in the concentrations in which they would be normally employed in bottle washing and like equipment to give the required sterilization for which purpose a concentration of the order of a 0.25 to 2% solution of a detergent containing 0.5 to 5% of the quaternary compound is required.

The invention is based on the discovery that tetra-alkyl quaternary ammonium halides or hydroxides in which two of the alkyl groups contain not less than six and not more than nine carbon atoms in each hydrocarbon group while the other two alkyl groups contain up to nine carbon atoms but preferably not more than three carbon atoms in each group, have the property of being compatible with all the alkaline detergent compounds other than silicate-containing detergents used in bottle washing and like equipment, such as alkaline hydroxides, carbonates and phosphates. Furthermore, while the compounds have not so high a bactericidal potency as the single long-chain alkyl compounds they have a sufficient bactericidal potency and detergent properties and do not foam in the concentrations in which they have to be employed to give the required sterilization.

It has further been found that water-soluble or water-miscible quaternary ammonium halides or hydroxides have the aforesaid properties if 30 one or more of the hydrogen atoms in the six to nine carbon alkyl chains are alkyl-substituted or if one or more of the hydrogen atoms in a six to nine carbon alkyl chain (other than a hydrogen atom attached to the omega carbon atom) in a seven to nine carbon atom chain is 35 substituted by an alkoxy alkyl or acylamino alkyl group or are alkyl chain groups containing a polar group and having six to nine straight chain carbon atoms in the chain.

40 According to the invention, a method of cleansing
and sterilizing milk bottles and like returnable
containers comprises scouring the said containers
45 with an aqueous solution containing a tetra-alkyl quaternary ammonium compound
having the following general formula:

wherein **X** is an anion. R_1 and R_2 are organic radicals selected from the group consisting of alkyls, alkoxy alkyls, acylamino alkyls including

alkyl chain groups containing a polar group, the said groups containing at least 7 and not more than 9 carbon linkages and including water soluble aryl substituents of the said radicals. R_3 and R_4 are selected from the same group of organic radicals as R_1 and R_2 but containing any number of carbon atoms up to nine and including water soluble aryl substituents of the said radicals.

According to a further feature of the invention there is provided a sterilizing detergent composition which in aqueous solution is of low surface tension and produces an unstable foam comprising an alkaline detergent other than a silicate-containing detergent and from 0.5 to 5 percent of a water-soluble or water-miscible alkyl quaternary ammonium halide or hydroxide whereof two of the alkyl groups each have not less than 6 nor more than 9 carbon atoms in the chain and the other two alkyl groups each have not more than three carbon atoms in the chain.

A quaternary ammonium compound selected from the above defined group when dissolved in water provides a composition with both bactericidal and considerable detergent properties without any other additions but it is preferred to use a compound of this group of quaternary ammonium compounds in association with a weak alkali or alkaline detergent other than a silicate-containing detergent whereby highly efficient cleansing may be effected with the use of only weak alkalis, such as sodium carbonate and moderate temperatures; accordingly the invention includes a detergent composition more particularly for cleaning bottles, which comprises a quaternary ammonium compound as above defined together with a weak alkali, such as sodium carbonate, instead of the usual strong alkali, such as sodium hydroxide.

A preferred composition for carrying out the method according to the invention comprises a tetra-alkyl quaternary ammonium halide or hydroxide in which two alkyl groups contain not less than six and not more than nine carbon atoms in each hydrocarbon group while the other two alkyl groups contain up to nine carbon atoms but preferably not more than three carbon atoms.

Conveniently, according to the invention, a quaternary ammonium compound may be a quaternary ammonium hydroxide such as N-hexyl-N-heptyl-N-propyl-N-methyl ammonium hydroxide.

It has been found that compounds as above described show excellent activity against the gram negative group of organisms as well as the gram positive group, being powerfully active against *B. coli*.

The following are examples of compositions suitable for the purpose according to the invention but are only instances of many compositions coming within the terms of the invention, which are equally suitable.

Example I

A sterilizing detergent for use in cleaning articles and apparatus used in the food industries may be prepared mixing 0.4 gram N-hexyl-N-heptyl-N-propyl-N-methyl ammonium hydroxide with 10 grams of sodium carbonate, 8 grams trisodium phosphate, this amount being sufficient for gallon of water.

Example II

A sterilizing detergent may be prepared for use in a bottle washing machine consisting of 40 to

80% Na_2CO_3 , 30 to 50% hydrated disodium phosphate in which is incorporated 1.0% of N,N-di-octyl, N,N dimethyl ammonium bromide.

Example III

A detergent consisting of 94% Na_2CO_3 , 5% Na_2PO_4 and 1% N,N,diethyl N,N,dimethyl ammonium bromide was used in 1% aqueous solution in a jet-type bottle washing machine at a temperature of 52° C. and during a run of one day using very dirty milk bottles every bottle taken from the machine was sterile.

Quaternary ammonium compounds as hereinbefore described in detergent compositions without caustic alkalis can be used in, for example, milk bottle washing equipment without any objectionable foaming and the bottles thus cleaned have lower bacterial counts than those normally obtained with detergents hitherto used and the bottle washing machines are maintained in a more sanitary condition than hitherto. Moreover, the machines can give the requisite sterilization at lower temperatures than hitherto employed thus preventing a great deal of the breakage of bottles. Furthermore, contamination of the rinsing sections of bottle washing machines is considerably reduced by carry-over of the bactericidal detergent. The quaternary compounds are without any detectable smell or taste in the concentrations used and are non-toxic to human beings.

The expressions "low surface tension" and "unstable foam" when used in this specification and in claiming clauses thereof mean that a solution of the sterilizing and detergent composition which is 0.0005 molar in respect of the quaternary ammonium halide or hydroxide has a surface tension against air less than 40 dynes per centimetre at pH 10.4 and when 100 cc. of such solution are briskly agitated with air in a closed cylinder no appreciable foam is visible after the cylinder has been allowed to stand for 1 minute.

What I claim is:

1. A method of cleansing and sterilizing milk bottles which comprises scouring the said bottles with a jet of an aqueous solution of N,N-di-octyl, N,N-di-methyl ammonium bromide.

2. A method of cleansing and sterilizing returnable food containers which comprises scouring the said containers with a jet of an aqueous solution containing a tetra-alkyl quaternary ammonium compound having the following general formula:

wherein X is an anion; R_1 and R_2 are octyl radicals; R_3 and R_4 are alkyl radicals selected from the group consisting of methyl, ethyl, propyl and butyl.

3. A sterilizing detergent composition which in aqueous solution is of low surface tension and produces an unstable foam after "composition" comprising an aqueous solution and which is suitable for scouring bottles with a jet thereof containing 0.5 to 5% by weight of the solution of alkyl quaternary ammonium compound having the following general formula:

wherein X is an anion; R_1 and R_2 are octyl radicals; R_3 and R_4 are alkyl radicals selected from

the group consisting of methyl, ethyl, propyl and butyl, together with a known detergent selected from the group consisting of sodium carbonate, trisodium phosphate and hydrated disodium phosphate.
